SCREW DRIVER

Stojan Naumovich, New York, N. Y.

Application July 24, 1936, Serial No. 92,279

5 Claims. (Cl. 145—50)

This invention relates to new and useful improvements in a combined scraper and screw driver for painters.

The invention has for an object the construction of an article as mentioned which is characterized by a flat metallic handle portion adapted to continue into a scraper blade, and a screw driver pivotally mounted on the rear end of said handle portion and adapted to assume a closed position against one side portion of said handle.

Still further the invention contemplates the provision of a means for limiting pivoting of the screw driver to an extended operative position.

Another one of the objects is to provide an arrangement whereby neither paint, putty, nor dirt may interfere with the complete opening of the screw driver.

Still further the invention proposes the provision of handle body elements associated with the flat metallic handle for giving the handle a better shape for gripping.

Another one of the objects is the provision of a means for holding the screw driver in its closed position, releasably, by moving one of the said handle body elements.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:—

Fig. 1 is an elevational view of a combined scraper and screw driver for painters constructed according to this invention.

Fig. 2 is a perspective view of the flat metallic handle and scraper with the screw driver portion and the body elements removed.

Fig. 3 is a perspective view of the screw driver per se.

Fig. 4 is an elevational view looking in the direction of the line 4—4 of Fig. 1.

Fig. 5 is a transverse sectional view taken on the line 5—5 of Fig. 1.

Fig. 6 is a transverse sectional view taken on the line 6—6 of Fig. 1.

Fig. 7 is a fragmentary side view of the top portion of Fig. 1 looking from the left side.

Fig. 8 is a fragmentary perspective view of a flat metallic handle for a combined scraper and screw driver constructed according to a modification of the invention.

Fig. 9 is a perspective view of the screw driver element per se for the device shown in Fig. 8.

Fig. 10 is a fragmentary elevational view partly shown in section of a combined scraper and screw driver constructed according to a modification of the invention.

Fig. 11 is a sectional view taken on the line 5—11 of Fig. 10.

Fig. 12 is a fragmentary perspective view of the flat metallic handle portion of a combined scraper and screw driver embodying another modification.

Fig. 13 is one of the brackets shown in Fig. 12.

Fig. 14 is a perspective view of the screw driver element per se.

In the form of the invention shown in Figs. 1—7 inclusive the combined scraper and screw driver for painters comprises a flat metallic handle portion 10 continuing into a scraper blade 11. At the junction between the handle portion and the scraper blade on both sides of the handle portion there are shoulders 12 and 13. From one of these shoulders, namely, the shoulder 13, a baffle strip portion 14 extends upwards and terminates at the top in a curved portion 15 concentric with an opening 16.

A handle body element 17 is secured upon one side of the flat metallic handle portion 10, the side having a shoulder 12. Another handle body element 18 is secured to the other side of the flat handle portion 10 to one side of the baffle element portion 14. Rivets 19 engage through the element 17, through openings 20 in the handle portion 10, and through the handle body element 18 for holding these parts together as a unit.

A screw driver blade 21 has a disc shaped base portion 22 formed with an opening 23. A rivet 24 engages through the opening 22 and the opening 16 for pivotally supporting the screw driver element. This screw driver element may be extended to the position shown in Figs. 1 and 7 in which position the screw driver may be used. It should be noted that the circular portion 15 of the baffle strip 14 terminates in a point 15' which prevents paint, putty and other foreign substances from collecting at this point and preventing the screw driver blade from opening completely.

In Figs. 8 and 9 a modified form of the invention has been disclosed in which the combined scraper and screw driver for painters 50 comprises a flat metallic handle portion 26 terminating in shoulder portions 27 and continuing into a scraper blade 28. The handle portion 26 is formed with a disc shaped projection 29 from one edge. A screw driver blade 30 is 55

shown in Fig. 9, and is formed with a fork shaped base end 31 the fingers of which are adapted to straddle the projection 29. A pintle rivet 32 is used for pivotally mounting the screw driver blade 30 on the handle. The dot and dash lines 30 in Fig. 8 indicate the folded position of the screw driver blade. It may be extended by pivoting it around to substantially 180°. The handle portion 26 is shown formed with openings 33 for rivets for attaching handle body elements (not shown on the drawings) but similar to the handle body elements previously described on the sides of the handle portion 26.

In Figs. 10 and 11 another modified form of the invention has been disclosed. In this form there is a flat metallic handle portion 26 which terminates at the bottom in shoulder portions 27 continuing into a blade 28. At the top portion at one side there is a projection 29 from the handle portion 26. A screw driver element 30' is associated with the handle portion and is pivotally mounted thereon by a rivet 32. Thus far the construction is identical to that shown in Figs. 8 and 9. Other details may be obtained from the prior disclosure.

There is now a departure from the previous form in the provision of handle body elements 36 fixedly attached by rivets 37 to the sides of the handle portion 26 only at the top areas. At the bottom areas there are additional handle body elements 36', but these are movably mounted. They are held in movable positions by rivets 38 which engage through slots 39 in the handle elements. It is these slots 39 that permit the handle elements to be moved. An expansion spring 40 is located within a recess 41 in each of the handle elements 36' and acts between the handle elements and one of the rivets for normally urging the handle elements 36' into raised position. These handle elements are provided with hook portions 42 at one of their sides engaging keeper recesses 43 in the screw driver blade 30 for locking the screw driver blade in the closed position.

Before the screw driver blade may be opened it is necessary that the handle elements 36' be manually moved down a short distance and the hooks 42 will disengage from the keeper recesses 43. The screw driver blade may be pivoted to the open position.

In Figs. 12-14 inclusive another modification of the invention has been disclosed in which there is a flat metallic handle portion 45 terminating at the bottom in shoulders 46 and continuing into a blade 47. At the top there are brackets 48 riveted to the sides of the handle portion. Between these brackets the base end portion 49' a screw driver blade 49 may engage. Openings 50 and 51 in the brackets and in the base portion 49' are adapted to receive a pintle rivet for pivotally supporting the screw driver. Handle body elements 52 are secured by rivets 53 to the sides of the handle portion 45.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. In a device of the class described, a handle,

comprising a flat metallic handle portion, a screw driver blade pivotally mounted on said metallic handle portion, a means for holding said blade in its closed position, comprising handle body elements fixedly mounted at the tops thereof to said handle portion, movably mounted handle body elements below said body elements, a spring normally urging said movable handle elements to a raised position, and a hook portion on said movably mounted handle elements engaging a keeper element in said blade in the raised position of said body element to hold said blade in a locked position.

2. In a device of the class described, a handle comprising a flat metallic handle portion, a screw driver blade pivotally mounted on said metallic handle portion, a means for holding said blade in its closed position, comprising handle body elements fixedly mounted at the tops thereof to said handle portion, movably mounted handle body elements below said body elements, a spring normally urging said movable handle elements to a raised position, and a hook portion on said movably mounted handle elements engaging a keeper element in said blade in the raised position of said body element to hold said blade in a locked position, said screw driver being the same thickness as the combined thickness of said metallic handle portion and said body elements and having its outer edge in the closed position thereof conforming with the outer edge of said metallic portion, whereby said screw driver, said body element, and said movably mounted body element form the complete handle.

3. In a device of the class described a handle, comprising a flat metallic handle portion, a screw driver blade pivotally mounted on said metallic handle portion, a means for holding said blade in its closed position, comprising handle body elements fixedly mounted at the tops thereof to said handle portion, movably mounted handle body elements below said body elements, a spring normally urging said movable handle elements to a raised position, and a hook on said movably mounted handle elements engaging a complementary recess in said blade in the raised position of said body elements to hold said blade in a locked position.

4. In a device of the class described, a handle, comprising a flat metallic handle portion, a screw driver blade pivotally mounted on said metallic handle portion, a means for holding said blade in its closed position, comprising handle body elements fixedly mounted at the tops thereof to said handle portion, movably mounted handle body elements below said body elements, a spring normally urging said movable handle elements to a raised position, and a hook portion on said movably mounted handle elements engaging a keeper element in said blade in the raised position of said body element to hold said blade in a locked position, said movable mounting of said body elements, comprising rivets in said metallic handle portion engaging into elongated slots in said movably mounted handle portion.

5. In a device of the class described, a handle, comprising a flat metallic handle portion, a screw driver blade pivotally mounted on said metallic handle portion, a means for holding said blade in its closed position, comprising handle body elements fixedly mounted at the tops thereof to said handle portion, movably mounted handle body elements below said body elements, a spring normally urging said movable handle elements to a

raised position, and a hook portion on said movably mounted handle elements engaging a keeper element in said blade in the raised position of said body element to hold said blade in a locked position, said movable mounting of said body elements comprising, rivets in said metallic handle

portion engaging into elongated slots in said movably mounted handle portions, said spring operating between one of said rivets and the end wall of a recess housing said spring in said movably mounted handle elements.
